UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

MOTOR-DRIVING MECHANISM FOR MOVING-PICTURE MACHINES.

1,209,492.

Specification of Letters Patent. Patented Dec. 19, 1916.

Application filed March 14, 1913. Serial No. 754,239.

To all whom it may concern:

Be it known that I, NICHOLAS POWER, a citizen of the United States, and resident of Brooklyn, in the county of Kings and State 5 of New York, have invented certain new and useful Improvements in Motor-Driving Mechanisms for Moving-Picture Machines, of which the following is a specification.

This invention relates to improvements in 10 motor driving mechanisms for moving picture machines and has for its object to provide a simple and efficient driving mechanism especially adapted for combination with a moving picture machine in such a 15 manner that it does not interfere with, or necessitate any alteration in said machine as constructed for the usual manual operation.

A further object of the invention is to provide 20 a driving mechanism which is readily controlled by the operator standing in his usual position for operating the machine, to give any desired speed to the moving films, and to maintain such speed smoothly and 25 uniformly.

Further objects of the invention reside in the provision of various improvements in the details of construction and will be hereinafter described in connection with the 30 accompanying drawings wherein I have illustrated a preferred embodiment of my invention in combination with a moving picture machine of modern design.

In the said drawings Figure 1 is a side 35 elevation of the motor and driving connections and the adjacent portions of the moving picture machine to which it is attached. Fig. 2 is an inverted plan view of the mechanism shown in Fig. 1. Fig. 3 is an end 40 view from the right of Figs. 1 and 2; and Fig. 4 is a side elevation on a reduced scale showing the greater portion of the moving picture machine and the relation of the driving mechanism thereto.

Referring now to the drawings in which like characters indicate like parts throughout the several views, 1 indicates the frame 45 of the machine here shown as comprising a square metal frame having at its lower corners brackets 2 for the reception of the supporting legs. The lower face of the square 1 is provided with suitable faces 3 against which is attached a bracket 5 from

which is suspended an electric motor 6 of usual construction having for its driving 55 wheel a friction disk 7 whose driving face is engaged by the periphery of a leather tired wheel 8 mounted for adjustment transversely of the disk 7 to vary the speed of rotation of the wheel. The wheel 8 is fast 60 to its axle 9 which is rotatably supported on bearings at the lower ends of the spaced arms of a hanger 10 depending from a cross rod 11 supported by an adjustable bracket 65 pivotally secured at its rear end to the fixed bracket 5. The adjustable bracket comprises two side arms 13 spaced apart by an integral web 14 a distance greater than the width of the bracket 5 with the web 14 immediately under and adjacent the lower face of 70 the bracket 5. For maintaining the bracket 12 in its adjusted position I provide a pair of adjusting screws 15 which pass freely through the web 14 and are threaded in the bracket 5 and a central adjusting screw 16 75 which is threaded in the web 14 and engages with its end the face of the bracket 5.

The bracket 12 is provided at one side with a depending ear 17 through which is threaded a set screw 18 engaging the rear 80 face of one of the arms of the hanger 10 and provided with a suitable lock nut to hold it firmly in the adjusted position. Tension springs 19 are connected at the lower ends of the arms of the hanger 10 to fixed 85 screws adjacent the upper face of the motor to hold the periphery of the wheel 8 in driving contact with the face of the disk 7 with a pressure determined by the adjustment of the screw 18 as will be readily understood. 90

The arms of the hanger 10 are provided with horizontal extensions 20 on either side of the wheel 8 and slidably mounted in the bearings in the ends of these arms is a rod 21 parallel with the shaft 9 of the wheel 8, 95 screws 20' being provided to vary the friction of the sliding movement of the rod. The rod 21 is slightly longer than the shaft 9 and is provided at its ends with arms 22 whose ends lie opposite the ends of the shaft 100 9 and are provided with studs 23 rotatably engaging the ends of the shaft 9 for causing the longitudinal movement of the shaft in synchronism with that of the rod with as little friction as possible. For holding 105 the arms 22 in proper position to engage

the shaft, one of the arms is provided with a pin 24 operating in a hole in the adjacent arm 20 to maintain the two in parallelism.

The rod 21 is provided with suitable stop 5 collars 25 for limiting the longitudinal movement of the rod and attached to one of these collars is a link 26 whose free end is pivotally connected to the lower end of the adjusting lever 27 fulcrumed on the 10 frame 1 in a convenient position for actuation by the operator as more particularly shown in Fig. 4 of the drawing. The shaft 9 has attached to it at one end beyond the arm 10 a pulley wheel 30 which is connected 15 by a suitable belt with a similar pulley wheel on the end of one of the rotating shafts of the projecting mechanism which I have indicated generally by the reference character 33.

20 The operation of my improved motor driving mechanism will be clear from the above description. In a machine of this kind it is essential that the drive be exceedingly smooth as the film which carries 25 the pictures to be projected is fragile and liable to be broken or damaged by any sudden stop or start of the machine. With my improved mechanism the pressure of the driving wheel against the disk 7 can be ad- 30 justed with the utmost nicety so that the friction surfaces will have the necessary adhesion for driving the film under normal conditions but will slip one on the other, in case of any abnormal resistance or excessive 35 driving impulse before the film can be damaged. Further, by means of the screws 15 and 16 the bracket 12 may be accurately ad- 40 justed to maintain the line of engagement of the wheel 8 and disk 7 exactly in line with the transverse diameter of the disk thereby obviating any angular strains on 45 the shaft 9 which add to its friction of rotation. This adjustment also permits the wheel 8 to be accurately centered on the disk 9 when it is desired to stop the machine without stopping the motor. Another desirable feature is the provision of the screws 20' by which the friction on the rod 21 can be adjusted to suit the personal

equation of the operator for obtaining the 50 smoothest starting and stopping of the machine possible.

Having thus described my invention, what I claim and desire to secure by Letters Patent is:—

1. In a moving picture machine the combination of a substantially rectangular hollow frame with two vertical and two horizontal sides, a film magazine inclosed in said frame, a projecting apparatus mounted on 60 the upper horizontal side of said frame, a driving motor suspended from the lower horizontal side of said frame, supporting legs at each corner of such side and connected thereto above the center of gravity 65 of the motor, a variable speed gear having driving connection with said motor, also suspended from said frame, a driving connection between said variable speed gear and said projecting apparatus, and means 70 for adjusting said speed gear comprising a lever pivotally mounted on the vertical face of said frame.

2. In a moving picture machine the combination of a substantially rectangular hollow metal frame having a rigid base, a film magazine inclosed in said frame, a projecting apparatus supported on the upper member of said frame and having a driving pulley projecting beyond the face of said magazine, an electric motor rigidly attached to and suspended from the base of said frame, supporting legs at each corner of such side and connected thereto above the center of gravity of the motor, and a variable speed 80 gear having driving connection with said motor, also suspended from said frame, and having a driven pulley beyond the face of said magazine with a driving belt connected 85 with said pulleys.

Signed at New York in the county of New York and State of New York this 11th day of March A. D. 1913.

NICHOLAS POWER.
